REFRIGERATED STORAGE HOUSE

Raymond H. Taylor, New York, N.Y., and Arthur P. Hillen, Heidelberg, Pa., assignors to Raymor Corporation, Pittsburgh, Pa., a corporation of Pennsylvania
Filed Dec. 7, 1961, Ser. No. 157,741
11 Claims. (Cl. 62—259)

This invention relates to refrigerated storage or warehouses, and particularly to a refrigerated storage or warehouse of simplified design having a semi-automatic material handling device incorporated therewithin.

The main object of the present invention is the provision of a new and improved structure for storing refrigerated articles.

Still another object of the present invention is the provision of a new and improved refrigerated warehouse having provision for the ready passage of the refrigerated air therethrough whereby to eliminate the need for elaborate duct work.

Yet a further object of the present invention is the provision of a new and improved material handling device especially useful in a refrigerated warehouse.

The above and other objects, characteristics and features of the present invention will be more fully understood in the following description taken in connection with the accompanying illustrative drawing.

In the drawings;

FIG. 1 is a plan view of a portion of a refrigerated warehouse embodying the present invention;

FIG. 2 is a sectional view taken along the line 2—2 in FIG. 1;

FIG. 3 is an end view of the material handling device for use in connection with the structure shown in FIGS. 1 and 2; and

FIG. 4 is a side elevational view of the material handling device.

Referring now to the drawings in detail, the refrigerated warehouse structure to be described herein is designated generally by the reference numeral 10. The structure includes two storage bays 12 and 14 which are spaced apart by an elongated elevator space or passageway 16. Each of the bays is a multi-storied structure having a plurality of vertically spaced floors 18 each of which has a number of air passages or apertures 20 therein. As will become obvious hereinafter, there is no need for air passages 20 in the first floor 18'. Preferably the floors 18 are made of pre-cast concrete, although, of course, in lieu thereof they may be made of poured-in-place concrete or of steel. As will be understood more fully hereinafter, the purpose of the apertures 20 is to provide easy air flow of refrigerated air from floor to floor, whereby to insure relatively uniform temperature throughout the entire structure. As used herein, the word "floor" is intended to mean floor, level, horizontal support structure and tier, as the structure, as already indicated, will not include a conventional floor, but instead, a horizontal structure having passages therethrough. The "floor" 18 may be a steel or concrete gridwork.

Disposed on the roof 22 of each of the bays 12 and 14 is a refrigerator 24 having an outlet 26 which passes through the roof to introduce refrigerated air at the top of each of the bays. Overlying the elevator space or passageway 16 is a suitable closure or shelter such as a shed-type roof 28. The structure is also provided with exterior thermal insulating walls 30 at both sides and ends of the bays but not on the sides confronting one another whereby there is easy passage of air from one bay to the other across the open elevator passage 16.

It will be seen that with the refrigerator units 24 disposed at the top of the structure and with the large elevator passageway 16 between the bays in free communica-

cation with both bays, and with the apertures 20 providing additional communication for the passage of air from floor to floor that the cold air introduced through the refrigerator outlets 26 can readily pass downwardly from floor to floor to thereby reach the bottommost floors of the building or warehouse 10 with little or no interference whereby to insure the easy circulation of cold air throughout the building without the incorporation of elaborate and costly duct work. This provides for a far simplified construction with a substantial economic saving therein. Underlying the building 10 is a base or foundation 23 having a central well portion 25 underlying the passage 16. Disposed on the well portion 25 are a pair of track rails 27 which are fixedly mounted to the well 25 in any suitable manner. Mounted on the rails 27 are wheels 29 which directly support the elevator structure 31 to be described hereinbelow.

The elevator structure 31 may assume any suitable form. However, as I showed herein, the elevator structure 31 is formed of four vertical members 32 disposed at the corners of the structure which are joined at vertically spaced intervals by horizontal members 33 to form a rigid rectangular vertically extending structure for which the elevator cab 36 may move up and down. Mounted on the support structure 31 is a suitable motor means 34 for actuating a lift mechanism here shown by way of example and not by way of limitation to be a hydraulic ram 35, having associated therewith a pulley and cable arrangement 37. Naturally, in lieu of a hydraulic lift, an electrical lift or any other suitable power lift may be employed. The motor 34 is also employed for imparting rotation to the wheels 29 carried by the bottom of the support structure 31 whereby to impart horizontal movement to the support structure on the rails 27.

Thus it will be seen that the elevator cab 36 is adapted to move vertically up and down under the power drive of the hydraulic mechanism 35 and the pulley arrangement 37 and is adapted to move horizontally through the passage 16 by actuation of the wheels 29 at the bottom of the elevator structure. In this manner, the elevator cab 36 can be brought to rest at any floor level in the structure and opposite any horizontal portion of such floor. It should be noted that as the elevator cab 36 and the over-all elevator support structure 31 is moved through the passage 16 it tends to stir up the refrigerated air passing through the structure 10 whereby to more effectively distribute it throughout the entire structure to thereby further enhance the ease of passage of the air throughout the structure.

It will be obvious that some duct work may be required to distribute refrigerated air coming from refrigerator units 24 horizontally along the space just beneath the roof of the structure in order to introduce such refrigerated air to areas horizontally remote from the units 24. However, with the exception of such horizontal duct work, no additional duct work is necessary and, especially, no vertical duct work is required to bring cold air to the lower levels of the building.

All the above structures including the combination of the bays with the vertically and horizontally movable elevator cab contribute to a simplified refrigerated warehouse having maximum passage and circulation of cold air therethrough. However, with an elevator structure of the type described, it becomes highly desirable to incorporate on said elevator structure the means for moving articles on to and off of said elevator structure whereby to eliminate any manual handling thereof. It becomes desirable furthermore to actually dispose the articles to be refrigerated on pallets whereby to space the article from the floors 18 to thereby minimize any impairment of cold air flow from floor to floor through the apertures 20. It will be obvious to those skilled in the

art that if refrigerated articles rested directly on the floor 18, they might well close the apertures 20 and thereby reduce the effectiveness of the circulation achieved by the novel structure.

The device for moving pallet support articles to be refrigerated onto and off of the elevator floor or cab 36 will be termed a dolly. The dolly is shown best in FIGS. 3 and 4 and reference will be had to these figures. The dolly structure is formed of conventional structural members such as channels, angles, or I-bars to provide the desired structural rigidity depending on the type of material to be refrigerated in the warehouse. As shown herein the dolly is formed of two outer channels 41 arranged with the channel webs facing outwardly towards the wheels 40 which movably supports the dolly structure. Upper angle irons 42 are secured within the channels 41 and lower angle irons 43 are secured against the upper angle irons 42 with a space 44 between the upper legs of angle irons 42 and 43 forming a guide. The manner of securement of these members may be any suitable manner such as nuts and bolts, rivets or welding. Channels 41 and angles 42 and 43 are also connected to one another by appropriate cross members 44 to thereby form an outer slide 45.

Mounted on the elevator platform or cab 36 are opposed pairs of inner and outer spaced angle irons 46 and 47 respectively as best seen in FIG. 3. The inner angle irons 46 have smaller upper angle irons 48 secured to the upstanding legs thereof in any suitable manner. It will be noted from the drawing that the angle irons 46, 47 and 48 are spaced with respect to each other to provide a track-way for Z beams 50.

Two spaced Z beams 50 having L beams 52 secured thereto are employed to form an inner slide 53 as will become more apparent hereafter. L beams 52 have bearing blocks 54 secured thereto, through which a shaft 55 extends. The shaft 55 is rotatably mounted on said L beams in any conventional manner. Pinions 56 along with sprocket wheels 57 are secured to shaft 55 for rotation therewith. A sprocket wheel and pinion assembly 57-56 is arranged near each end of the slides 45 and 53 as viewed in FIG. 4. Upper moveable rack 60 is secured along the longitudinal axis beneath the top surface of slide 45 and a stationary rack 61 is secured to the elevator platform 36. Racks 60 and 61 extend substantially the length of the slides 45 and 53 and are at least as long as the distance between the outer circumference of pinion 56 as viewed in FIG. 4.

A sprocket chain 62 is trained over sprocket wheels 57 so that rotation of either of the sprocket wheels 57 will be imparted to the other.

Extending from opposite ends of inner slide 53 as best seen in FIG. 4, is a left hand cable portion 65 and a right hand cable portion 66, the center of the cable being wrapped around a drum 70 as will be described presently. Cable portions 65 and 66 are trained over suitable pulleys 67 and 68 respectively, arranged at their points of change of direction, and the cables are connected at their point of mutual joining opposite to their points of connection with inner slide 53, to drum 70 which is suitably mounted in rotation by a reversible motor selectively driving the drum in opposite directions. Drum 70 and its drive motor are mounted in a conventional fashion beneath the elevator platform 36.

Disposed above the outer slide 45 are a pair of channels 75 which are connected to one another at spaced intervals by cross beams 78 whereby to form a rigid jack frame. Engaging the undersides of the channels 75 are the moveable members 80 of jacks 82 having their stationary members 84 secured to the top 44 of the outer slide 45 under at least the four corners of the jack frame. Suitable means for raising and lowering the jacks, such as a hydraulic actuator 86 is provided to simultaneously raise and lower the jacks 82 whereby to raise and lower the

jack frame 75. The jack frame 75 is adapted to fit under a conventional pallet whereupon it may be raised by the jacks which are positioned on all four corners of the jack frame and thereby lift the pallet off the floor.

To describe the operation of the material handling apparatus incorporated in the warehouse 10, let it be assumed that a pallet 90 is resting on the first floor 18' and is to be moved from the first floor of bay 12 to the third floor 18''' of bay 14 at a predetermined location on said third floor. The elevator structure 31 is moved by the wheels 29 until the elevator floor 36 is in horizontal alignment with the pallet 90. Simultaneously, the elevator is lowered to bring the dolly into registry with the opening in the pallet. At this time the jack frame 75 is in its lowered position to enable it to pass under the pallet.

The drum 70 is thereupon rotated in a counter-clockwise direction whereby to pull in on the cable portion 66 and to let out on the cable portion 65 to thereby move the inner slide 53 to the left as viewed in FIG. 4. The movement of the inner slide will cause a concomitant movement of the outer slide 45. However, in addition to the concomitant movement, due to the inclusion of the sprocket 56 which will rotate because of movement of the inner slide 53 and the engagement of sprockets 56 (or either of them) with stationary rack 61 they will impart additional motion of the outer slide relative to the inner slide. Accordingly, the outer slide will have a motion that will be far greater in distance than the inner slide which motion will be equal to the motion imparted by movement of the inner slide itself and further the motion imparted by virtue of the rotation of the sprockets 56. The movement of the dolly and particularly the movement of the outer slide 45 is continued until the jack frame has passed under the pallet 90 at which time the movement is stopped by deenergizing the motor means rotating the drum 70. The hydraulic motor 86 is then actuated to raise the jacks 82 whereby to lift the jack frame 75 to bring it into engagement with the bottom of the pallet and then lift the pallet off the floor 18'. Upon this occurring, the motor means is again actuated to rotate the drum 70 in a counter-clockwise direction whereby to pull in on the cable portion 65 and to pay out on the cable portion 66 to thereby cause the inner carriage member 53 to move to the right as viewed in FIG. 4. The movement of the inner carriage 53 to the right will cause the sprockets 56 to rotate in a clockwise direction whereby to impart not only the movement of the inner carriage to the outer carriage but to impart an additional movement due to the inter-engagement of the sprockets or gears 56 with the racks 60 and 61. This will return the dolly with the pallet carried thereon to the elevator floor 36.

The elevator will then be moved to the left or to the right by operation of the elevator wheels 29 on the tracks 27 and the elevator will be raised to bring the elevator floor 36 in registry with the floor 18'. Thereupon the motor driving the drum 70 is actuated to rotate the drum in a counter-clockwise direction to move the inner carriage to the right and hence to move the outer carriage 45 to the right at a more rapid rate and for a greater distance. The movement of the outer carriage 45 to the right will continue until the pallet 90 is located over desired portion of the floor 18''' of the bay 14 whereupon the movement is discontinued. At that point the hydraulic motor means 86 is actuated to lower the jacks 82 to move the pallet downwardly onto the floor and the jack frame continues moving downwardly until it becomes disengaged from the pallet. At that point the dolly can be moved leftward in a manner already described to return it to the elevator.

From the foregoing description, it will be seen that a convenient semi-automatic material handling dolly has been incorporated into the warehouse for efficient handling of the material to be cold-stored whereby to quickly and economically handle such material as it need be handled. Thus it will be seen that the warehouse structure described herein is not only highly economical to

build due to the elimination of ducts and the incorporation of a moveable elevator of the type described for enhancing the flow of cold air through the building but is inexpensive to operate due to the decreased amount of labor necessary to handle goods within the warehouse. The problem of labor in such warehouses is often significant due to the fact that generally premiums must be paid for workers working under such adverse temperature conditions.

It will be understood that although this description has been limited to a refrigerated structure, it is equally applicable to a structure having a refrigerated section and a non-refrigerated section. In such a structure, the two sections would be separated by an insulated wall extending transversely of passageway 16, and moveable insulated doors, which when opened, will permit elevator structure 31 with elevator 36 thereon to pass between the two sections. Naturally, the non-refrigerated section will not require its exterior walls to be thermal insulating.

While I have herein shown and described the preferred form of the present invention, it will be understood that various changes and modifications may be made therein within the scope of the intended claims without departing from the spirit and scope of this invention.

What we claim is:

1. A cold storage warehouse comprising a plurality of vertically spaced stories surrounded by vertical surfaces, means for supporting said vertically spaced stories in said vertically spaced relation, a passage alongside of one vertical surface of said structure, said passage being in direct communication with the space between said stories, a vertically and horizontally movable elevator in said passage for transporting material from one story to another, each story of said structure being of substantially greater width than the width of said elevator and a refrigeration unit disposed on the roof of said structure, said refrigeration unit having a discharge outlet directed into the top story only of said structure.

2. A cold storage warehouse comprising a support structure having a plurality of vertically spaced floors with a plurality of vertically extending passages extending through each of them above the first floor, means for supporting said plurality of floors in vertically spaced relation, and a refrigeration unit disposed on the roof of said warehouse and having a discharge outlet for discharging refrigerated air only in the space above the top floor of said structure, another passage, said other passage being disposed alongside of said support structure, and being in direct communication with the space between said floors, said other passage being in direct communication with the space between said floors, and a vertically and horizontally movable elevator disposed in said other passage alongside said support structure for transporting material from one floor of said structure to another each floor of said structure being of substantially greater width than the width of said elevator.

3. A cold storage warehouse comprising an enclosed building having two spaced apart bays with a passage therebetween, each of said bays having a plurality of vertically spaced floors with a plurality of vertically extending passages extending through each of them above the first floor, said passage being in direct communication with the space between said floors, means for supporting said plurality of floors in vertically spaced relation, and a refrigeration unit disposed on the roof of said building and having a discharge outlet for discharging refrigerated air only in the space above the top floor of said building, each floor of said building being of substantially greater width than the width of said elevator and a vertically and horizontally movable elevator disposed in said passage between said bays for transporting material from one floor of said building to another, said passage between said bays being in direct communication with the space between said floors.

4. A cold storage warehouse comprising a support structure, a plurality of vertically spaced floors supported by said support structure, said floors having a plurality of vertically extending passages extending through each of them above the first floor and a refrigeration unit disposed on the roof of said warehouse and having a discharge outlet for discharging refrigerated air only into the space above the top floor of said structure, another passage alongside of said support structure, said other passage being in direct communication with the space between said floors and a vertically and horizontally movable elevator disposed in said passage alongside said support structure for transporting material from one floor of said structure to another, each floor of said structure being of substantially greater width than the width of said elevator, said passage between said floors being in direct communication with the space between said floors and means on said elevator for transferring material onto and off of said elevator, said means comprising first slide means supported for reciprocation by said elevator, second slide means reciprocally extensible from said first slide means; means for extending and withdrawing said first slide means; and rack and pinion means between said first slide means and said second slide means to effect reciprocation of said second slide means in response to movement of said first slide means, whereby said first and second slide means may be simultaneously extended or retracted.
5. A cold storage warehouse comprising a support structure, a plurality of vertically spaced floors supported by said support structure, said floors having a plurality of vertically extending passages extending through each of them above the first floor, and a refrigeration unit disposed on the roof of said warehouse and having a discharge outlet for discharging refrigerated air only into the space above the top floor of said structure, another passage alongside of said support structure and being in direct communication with the space between said floors, and a vertically and horizontally movable elevator disposed in said other passage alongside said support structure for transporting material from one floor of said structure to another, and means on said elevator for transferring material onto and off of said elevator, said means comprising first slide means supported for reciprocation by said elevator, second slide means reciprocally extensible from said first slide means; means for extending and withdrawing said first slide means; and gear means between said first slide means and said second slide means to effect reciprocation of said second slide means in response to movement of said first slide means, whereby said first and second slide means may be simultaneously extended or retracted, said gear means including rotatable means rotatably supported on said first slide means for rotation upon reciprocation of said first slide means and rack means secured to the slide means upon which said rotatable means are not supported, said rack means contacting said rotatable means so that the rotary motion of said rotatable means is converted to reciprocal motion of the slide means upon which said reciprocable rack means are secured.
6. A cold storage warehouse comprising an enclosed building having two spaced apart bays with a passage therebetween, each of said bays having a plurality of vertically spaced floors with a plurality of vertically extending passages extending through each of them above the first floor, means for supporting said plurality of floors in vertically spaced relation, and a refrigeration unit disposed on the roof of said building and having a discharge outlet for discharging refrigerated air only into the space above the top floor of said building, and a vertically and horizontally movable elevator disposed in said passage between said bays for transporting material from one floor of said building to another, said passage between said bays being in direct communication with the space between said floors, and means on said elevator for transferring material onto and off of said elevator, said means comprising first slide means supported for reciprocation by said elevator, second slide means reciprocally extensible from said first slide means; means for extending and withdrawing said first slide means; and gear means between said first slide means and said second slide means to effect reciprocation of said second slide means in response to movement of said first slide means, whereby said first and second slide means may be simultaneously extended or retracted, said gear means including rotatable means rotatably supported on said first slide means for rotation upon reciprocation of said first slide means and rack means secured to the slide means upon which said rotatable means are not supported, said rack means contacting said rotatable means so that the rotary motion of said rotatable means is converted to reciprocal motion of the slide means upon which said reciprocable rack means are secured.

comprising first slide means supported for reciprocation by said elevator; second slide means reciprocally extensible from said first slide means; means for extending and withdrawing said first slide means; and gear means between said first slide means and said second slide means to effect reciprocation of said second slide means in response to movement of said first slide means, whereby said first and second slide means may be simultaneously extended or retracted, said gear means including rotatable means rotatably supported on said first slide means for rotation upon reciprocation of said first slide means and rack means secured to the slide means upon which said rotatable means are not supported, said rack means contacting said rotatable means so that the rotary motion of said rotatable means is converted to reciprocal motion of the slide means upon which said rack means are secured, and means carried by said second slide means and movable vertically relative thereto.

7. A warehouse comprising a support structure having a plurality of vertically spaced floors with a plurality of vertically extending passages extending through each of them above the first floor, another passage, said other passage being disposed alongside said support structure and being in direct communication with the space between said floors, a vertically and horizontally movable elevator disposed in said other passage alongside said support structure for transporting material from one floor of said structure to another, each floor of said structure being of substantially greater width than the width of said elevator, means for effecting transfer of material from one location to another location comprising: first slide means supported for reciprocation at one of said locations; second slide means reciprocally extensible from said first slide means; means for extending and withdrawing said first slide means; and rack and pinion means between said first slide means and said second slide means to effect reciprocation of said second slide means in response to movement of said first slide means, whereby said first and second slide means may be simultaneously extended or retracted.

8. The warehouse as in claim 7 in which said rack and pinion means comprises: rotatable means rotatably supported on said first slide means for rotation upon reciprocation of said first slide means and reciprocable rack means secured to the said second slide means, said reciprocable rack means contacting said rotatable means so that the rotary motion of said rotatable means is converted to reciprocal motion of said second slide means.

9. The warehouse as in claim 8 in which said rack and pinion means further comprises fixed rack means are secured adjacent said rotating means and in contact therewith, said fixed rack means engaging said rotating means to initiate rotation thereof upon movement of the slide means upon which said rotatable means are supported.

10. A warehouse comprising a support structure having a plurality of vertically spaced floors with a plurality of

vertically extending passages extending through each of them above the first floor, another passage, said other passage being disposed alongside said support structure and being in direct communication with the space between said floors, a vertically and horizontally movable elevator disposed in said other passage alongside said support structure for transporting material from one floor of said structure to another, each floor of said structure being of substantially greater width than the width of said elevator, a materials handling carriage for effecting transfer of materials from a loading point to an area in which the carriage is mounted, said carriage comprising: a fixed rack secured to the area in which the carriage is mounted; an inner slide movable over said rack; a pinion rotatably supported on said inner slide and engaging said fixed rack; an outer slide movably mounted with respect to said inner slide; a movable rack fixedly secured to said outer slide for movement therewith, and in engagement with said pinion; and motive means effecting movement of said inner slide, whereby upon movement of said inner slide under the influence of said motive means, said outer slide will be extended as a result of the movement of said pinion.

11. A cold storage warehouse comprising a support structure having a plurality of vertically spaced floors with a plurality of vertically extending passages extending through each of them above the first floor, means for supporting said plurality of floors in vertically spaced relation and a refrigeration unit having a discharge outlet for discharging refrigerated air into the space above the top floor of said structure, another passage, said other passage being disposed alongside of said support structure and being in direct communication with the space between said floors and a vertically and horizontally movable elevator disposed in said other passage alongside said support structure for transporting material from one floor of said structure to another, each floor of said structure being of substantially greater width than the width of said elevator.
